UNITED STATES PATENT OFFICE.

ALGER R. FRIBERG, OF APPLETON, WISCONSIN.

NECK YOKE.

Application filed July 25, 1921. Serial No. 487,327.

To all whom it may concern:

Be it known that I, ALGER R. FRIBERG, a citizen of the United States, residing at Appleton in the county of Outagamie and State 5 of Wisconsin, have invented certain new and useful Improvements in Neck Yokes; and I do declare the following to be a full, clear, and exact description of the invention, such as will enable others skilled in the art 10 to which it appertains to make and use the same.

My invention relates to improvements in neck yokes and more particularly to those of relatively small size adapted for detachable connection to the ends of the larger neck yoke which is connected with the tongue, so as to equally distribute the weight upon the hames of the team. Numerous devices have been provided for detachably 20 connecting the smaller yokes with the usual neck yoke, but most of these devices, while preventing accidental release of the yokes, have been very difficult to release when the yokes must be disconnected, often requiring 25 that the teamster remove his gloves or mittens, which is very undesirable in cold weather.

The object of my invention is to provide an extremely simple and inexpensive, yet a 30 highly efficient and desirable arrangement of parts for preventing accidental release of the supplemental yokes from the main yoke, regardless of the position to which the supplemental yokes are moved, novel provision 35 being made, however, whereby the latch device may be quickly and easily released when necessary.

With the foregoing in view, the invention resides in the novel construction and combination of parts hereinafter described and claimed, the descriptive matter being supplemented by the accompanying drawings.

Figure 1 is a plan view partly in horizontal section showing a neck yoke embodying my improvements.

Figure 2 is an edge elevation.

Figure 3 is a sectional view as indicated by line 3—3 of Fig. 1.

In the drawings above briefly described, 50 the numeral 1 designates a neck yoke which preferably is constructed from wood, the ends of said yoke being provided with rings or the like 2, while its central portion is equipped with a hook 3, for co-action with 55 one of the usual neck yoke rings on the larger yoke which is carried by the tongue.

The shank of the hook 3 is provided with a slot 4 and the bill 5 of said hook is turned inwardly toward one end portion of the yoke, being terminated in spaced relation 60 with the latter as shown clearly in Figure 1. While any suitable means may be employed for securing the hook 3 to the yoke 1, I prefer to equip said hook with an integral ring 6 surrounding said yoke and held against 65 turning thereon by a screw or the like 7.

A resilient latch rod 8 is secured at one end to the yoke 1, preferably by bending one end of said rod laterally to form a prong 9 and driving said prong into the yoke as disclosed in Figure 1. The rod 8 passes through the slot 4 and across the end of the bill 5, the free end of said rod being shaped to form an appropriate handle 10 by means of which the rod may be moved inwardly to 75 the dotted line position shown in Figure 1 whenever it is necessary to release the hook 3 from the ring with which it co-acts.

From the foregoing, taken in connection with the accompanying drawings, it will be 80 seen that I have provided an extremely simple and inexpensive device which may be expeditiously manufactured and which will be highly efficient and desirable in use. Particular attention is directed to the fact that 85 the latch rod 8 cannot become accidentally released, no matter to what position the yoke 1 is moved. Furthermore, this rod may be easily released when necessary without requiring that the teamster remove his gloves 90 or mittens.

Since excellent results have been obtained from the details disclosed, they are preferably followed. It is to be understood, however, that within the scope of the invention 95 as claimed, numerous minor changes may be made. Furthermore, while I have disclosed my invention in connection with a neck yoke, it is to be understood that it is adaptable also to singletrees and the like, should such 100 application be found desirable. Also, the spring 8 may be attached to the yoke in any suitable way.

I claim:

1. A yoke having a hook whose bill turns 105 inwardly toward the yoke and whose shank is provided with a longitudinal slot having parallel sides, and a spring wire arm extending through the slot of said shank and across the end of said bill and being held against 110 lateral displacement from said bill by the parallel sides of said slot.

2. A yoke having a hook whose bill turns inwardly toward the yoke and whose shank is formed with a longitudinal slot having parallel sides, and a spring wire arm diverging with respect to the yoke and passing through said slot; one end of said arm being laterally bent and driven into the yoke to attach said arm, the other end of said arm extending across and beyond the end of said

hook bill and being held against lateral displacement from said bill by the parallel sides of said slot, the free end of said arm being bent into the form of a loop constituting a handle spaced from the hook for forcing said arm away from the hook bill. 10 15

In testimony whereof I have hereunto set my hand.

ALGER R. FRIBERG.
